UNITED STATES PATENT OFFICE.

THURE E. DAHL, OF NEW YORK, N. Y.

DESIGN FOR A WALL BRACKET FOR LIGHTING FIXTURES.

Application filed June 9, 1922. Serial No. 2,601. Term of patent 7 years.

To all whom it may concern:

Be it known that I, THURE E. DAHL, a subject of the King of Sweden, and residing at New York, in the county of New York and State of New York, have invented a new, original, and ornamental Design for a Wall Bracket for Lighting Fixtures, of which the following is a specification, reference being had to the accompanying drawing, forming part thereof.

Fig. 1 is a side view of a wall bracket for lighting fixtures, showing my new design.

Fig. 2 is a front elevation view of the plate of my wall bracket, the arm shown in Fig. 1 as being attached to the plate, being broken away.

I claim:

The ornamental design for a wall bracket for lighting fixtures, as shown.

THURE E. DAHL.
